E. HILL

ROTARY PUMP

Filed Oct. 24, 1923

UNITED STATES PATENT OFFICE.

EBENEZER HILL, OF SOUTH NORWALK, CONNECTICUT, ASSIGNOR TO THE HILL COMPRESSOR & PUMP COMPANY, OF NEW YORK, N. Y., A CORPORATION OF DELAWARE.

ROTARY PUMP.

Application filed October 24, 1923. Serial No. 670,453.

To all whom it may concern:

Be it known that I, EBENEZER HILL, a citizen of the United States, residing at South Norwalk, in the county of Fairfield and State of Connecticut, have invented a new and useful Improvement in Rotary Pumps, of which the following is a specification.

This invention relates to rotary pumps of the gear type, that is, those pumps which have a rotor driving intermeshing gears for pumping or compressing fluids, more particularly air and gases, although adapted for other fluids.

The object of the invention is to provide such a pump with simple means for preventing leakage across the faces of the gear teeth of the fluid being pumped, which means retain the working elements sufficiently free to enable the pump to start easily and speed up quickly, but which are so designed that the tightness of the joints subject to leakage is automatically increased and efficient lubrication is ensured as the pressure generated builds up, thus permitting the parts to be made with less accuracy and fitted less closely than otherwise would be required, thereby reducing the cost of manufacture, minimizing the operating power, and rendering the pump especially adapted for pumping light gases or compressing fluids to a high degree.

This object is attained by designing the rotor which contains and drives the internally toothed gear and the cooperating externally toothed driven gear of different number of teeth, in such manner that it may float with the gears axially in the casing and these parts be forced against the head which is attached to the casing over the pumping chamber, a spring being arranged to cause the initial pressure of the parts against the head with sufficient closeness to allow the pressure to build up without causing undue friction, and pipe connections being made so that the pressure of the pumped fluid will be exerted on the back of the rotor to supplement the spring tension and keep the joints tight with a force depending upon the discharge pressure, which connections also conduct lubricant into the casing and allow it under the pressure to be forced between the wearing surfaces so as to at the same time reduce

the friction and pack the joints against leakage of the fluid being pumped.

In the accompanying drawings Fig. 1 shows a central longitudinal section of a pump constructed according to the invention. Fig. 2 shows a face view of the pump with the head removed.

The casing 1 which is generally circular in outline contains a cylindrical pumping chamber 2 that is closed on one end by a head 3 which is fastened to the casing by any suitable means. The casing has an intake passage 4 on one side and a discharge passage 5 on the other side while the head has an intake port 6 leading from the intake passage to the pumping chamber, and a discharge port 7 leading from the pumping chamber to the discharge passage. Rotatably fitting and having a slight movement axially in the pumping chamber is a rotor 8. The hub 9 of the rotor is mounted on anti-friction bearings 10 the inner ring 11 of which is fastened to the hub while the outer ring 12 is fitted so that it may have a slight axial movement in the casing. The driving shaft 13 is splined in the hub of the rotor so that while the shaft will rotate the rotor it will not interfere with the axial movement of the rotor.

Fastened in the rotor is an internally toothed gear 14 and engaging the teeth of this gear are the teeth of an externally toothed gear 15. The externally toothed gear is mounted on anti-friction bearings 16 that are supported by a stud 17 fastened in the head. The stud is positioned out of line with the driving shaft so that the axis of the externally toothed gear will be eccentric to the axis of the internally toothed gear. One of these gears has more teeth than the other and they coact in a well known manner to effect the pumping or compression of fluids.

A spring 18 is arranged in a cavity 19 in the casing that communicates with the pumping chamber, in such manner that the spring thrusts against the outer race ring 12 and through the bearing presses the edge of the rotor and the faces of the pumping gears against the inner face of the head. Lubricant is introduced into this cavity. Leading from the reservoir 20 into which the fluid is pumped, to the cavity containing the spring is a pipe 21. The function of

this connection is to admit discharge pressure to the cavity and permit it to be exerted on the back of the rotor. This connection also is adapted to conduct back lubricant which has been forced through the joints between the wearing surfaces and is passed out through the discharge pipe. A common type of gland packing 22 is arranged in the end of the casing to prevent leakage from the spring cavity around the driving shaft. With this construction the rotor and the gears are initially pressed against the head by the spring with just sufficient force to prevent leakage of the pumped fluid across the faces of the gear teeth when the pump is started. This enables the pump to be started easily. As the pressure builds up by the continued operation of the pump the discharge pressure is exerted on the back of the rotor and this pressure supplements and soon becomes greater than that of the spring and keeps the joints tight with a force proportional to the accumulated discharge pressure. If there were no spring to provide the initial pressure and no discharge pressure as when starting up the pump, in order to have the joints sufficiently tight to accumulate pressure it would be necessary to bore the pumping chamber to a very exact diameter and depth, and face off the rotor and gears with great accuracy so that they would bear perfectly on the inner face of the head. Under such conditions the parts would fit so closely that there would be an undue amount of friction, resulting in the requirement of an unnecessary amount of power. By having the rotor float and initially kept tight by the spring the parts may be fitted relatively loose, for the spring will hold the parts sufficiently close to permit of the necessary accumulation of pressure, and as the discharge pressure accumulates the required seal will be effected by the fluid pressure. Lubricant filled into the spring cavity is carried by the discharge pressure, between the working surfaces so as to reduce the friction and liquid seal the joints. Such lubricant as passes through the pump is returned to the spring chamber so that a continuous and efficient lubricating circulation is ensured. With this arrangement for sealing and lubricating the joints the wearing surfaces do not have to be fitted with great exactness, as would otherwise be required, for there is sufficient initial pressure exerted by the spring to permit the discharge pressure to accumulate and as the discharge pressure accumulates the tightness of the joints is increased proportionately, so that the pump will compress fluids up to the limit of its strength or limit of the driving power applied.

The invention claimed is:

65 1. A rotary pump comprising a casing containing a pumping chamber, a ported head closing one end of said chamber, said head having an intake to and discharge from the chamber, a rotor having one side closed and the other side open, rotatable in and having an axial movement in said chamber so the open side will bear against the inner face of the head, means located in and actuated by the rotor for pumping fluid, a spring for initially forcing the rotor and pumping means axially toward the head, and means for conducting pressure accumulated by the pump to the back of the rotor for supplementing the tension of said spring and forcing the rotor against the head according to the accumulated pressure.

2. A rotary pump comprising a casing containing a pumping chamber, a ported head closing one end of said chamber, said head having an intake to and discharge from the chamber, a rotor having one side closed and the other side open, rotatable in and having an axial movement in said chamber so the open side will bear against the inner face of the head, internally toothed and externally toothed intermeshing gears located in and actuated by the rotor for pumping fluid, a spring for initially forcing the rotor and gears axially toward the head, and means for conducting pressure accumulated by the pump to the back of the rotor for supplementing the tension of said spring and forcing the rotor against the head according to the accumulated pressure.

3. A rotary pump comprising a casing containing a pumping chamber and a pressure chamber communicating with the pumping chamber, a ported head closing one end of said pumping chamber, said head having an intake to and discharge from the pumping chamber, a rotor having one side closed and the other side open, rotatable in and having an axial movement in the pumping chamber so the open side will bear against the inner face of the head, means located in and actuated by the rotor for pumping fluid, a spring for initially forcing the rotor and pumping means axially toward the head, and means for conducting discharge pressure to the pressure chamber back of the rotor, and thereby forcing the rotor against the head according to the degree of discharge pressure.

4. A rotary pump comprising a casing containing a pumping chamber, a ported head closing one end of said chamber, said head having an intake to and discharge from the chamber, a rotor having one side closed and the other side open, rotatable in and having an axial movement in said chamber so the open side will bear against the inner face of the head, means located in and actuated by the rotor for pumping fluid, and means for conducting pressure accumulated by the pump to the back of the rotor and

thereby forcing the rotor and pumping means against the head according to the accumulated pressure.

5. A rotary pump comprising a casing containing a pumping chamber, a ported head closing one end of said chamber, said head having an intake to and discharge from the chamber, a rotor having one side closed and the other side open, rotatable in and having an axial movement in said chamber so the open side will bear against the inner face of the head, internally toothed and externally toothed intermeshing gears located in and actuated by the rotor for pumping fluid, and means for conducting pressure accumulated by the pump to the back of the gears for forcing them against the head with a pressure depending on the degree of accumulated pressure. 70
- 10 6. A rotary pump comprising a casing containing a pumping chamber, a spring chamber communicating with the pumping chamber and a passage from the pump discharge to said chamber, a ported head closing one end of said pumping chamber, said head having an intake to and discharge from the pumping chamber, a rotor having one side closed and the other side open rotatable in and having an axial movement in said chamber so the open side will bear against the inner face of the head, means located in and actuated by the rotor for pumping fluid, and a spring located in said spring chamber for, in conjunction with the discharge pressure, forcing the rotor axially toward the head. 85
- 15 7. A rotary pump comprising a casing containing a pumping chamber, a ported head closing one end of said chamber, said head having an intake to and discharge from the chamber, a rotor having one side closed and the other side open rotatable in and having an axial movement in said chamber so the open side will bear against the inner face of the head, internally toothed and externally toothed intermeshing gears movable axially with the rotor and rotated thereby for pumping fluid, a spring for initially forcing the rotor axially toward the head, and means for conducting pressure accumulated by the pump to the back of the rotor for supplementing the tension of said spring. 90
- 20 8. A rotary pump comprising a casing containing a pumping chamber, a ported head closing one end of said chamber, said head having an intake to and discharge from the chamber, internally toothed and externally toothed intermeshing gears rotatable in said chamber, anti-friction bearings supporting the gears, said bearings permitting an axial movement of said gears in said chamber so they may bear against the inner face of the head, means for rotating said gears, a spring for initially forcing the gears axially toward the head, and means for conducting pressure accumulated by the pump to the back of the gears for forcing them against the head with a pressure depending on the degree of accumulated pressure. 95
- 25 9. A rotary pump comprising a casing containing a pumping chamber with an intake to and discharge from said chamber, a head closing one end of said chamber, a rotor having one side closed and the other side open, rotatable in and having an axial movement in said chamber, internally toothed and externally toothed intermeshing gears movable axially with and rotated by the rotor for pumping fluid, and means for conducting pressure accumulated by the pump to the back of the rotor and forcing the gears against the head according to the accumulated pressure. 100
- 30 10. A rotary pump comprising a casing containing a pumping chamber with an intake to and discharge from said chamber, a driving shaft, a rotor rotatable in and capable of an axial movement in said chamber, means connecting the shaft and rotor whereby the shaft will rotate the rotor but not interfere with its axial movement, means actuated by the rotor for pumping fluid, a spring for initially forcing the rotor axially toward one end of the pumping chamber, and means for conducting pressure accumulated by the pump to the back of the rotor for supplementing the tension of said spring. 105
- 35 11. A rotary pump comprising a casing containing a pumping chamber with an intake to and discharge from said chamber, a driving shaft, a rotor rotatable in and capable of an axial movement in said chamber, means connecting the shaft and rotor whereby the shaft will rotate the rotor but will not interfere with its axial movement, internally toothed and externally toothed intermeshing gears actuated by said rotor for pumping fluid, a spring for initially forcing the rotor and gears axially toward one end of the pumping chamber, and means for conducting pressure accumulated by the pump to the back of the rotor for supplementing the tension of said spring. 110
- 40 12. A rotary pump comprising a casing containing a pumping chamber with an intake to and discharge from said chamber and a pressure chamber communicating with the pumping chamber, a driving shaft, a rotor rotatable in and capable of an axial movement in said chamber, means connecting the shaft and rotor whereby the shaft will rotate the rotor but not interfere with its axial movement, means actuated by said rotor for pumping fluid, a spring in said pressure chamber for initially forcing the rotor 115
- 45 130

axially toward one end of the pumping chamber, and means for conducting discharge pressure from the pump to the pressure chamber back of the rotor.

5 13. A rotary pump comprising a casing having a pumping chamber with an intake to and discharge from said chamber, a driving shaft, a rotor rotatable in and capable of an axial movement in said chamber, 10 means connecting the shaft and rotor whereby the shaft will rotate the rotor but not interfere with its axial movement, means actuated by said rotor for pumping fluid, and means exerted against the back of 15 the rotor for forcing the rotor axially against one wall of the pumping chamber.

14. A rotary pump comprising a casing having a pumping chamber with an intake to and discharge from said chamber, a driving shaft, a rotor rotatable in and capable of an axial movement in said chamber, means connecting the shaft and rotor whereby the shaft will rotate the rotor but not interfere with its axial movement, means actuated by said rotor for pumping fluid, and means for conducting pressure accumulated by the pump to and against the back of the rotor for forcing the rotor axially against one wall of the pumping chamber.

30 15. A rotary pump comprising a casing having a pumping chamber with an intake to and discharge from said chamber, a pressure chamber, means connecting the discharge from the pumping chamber with the 35 pressure chamber, a driving shaft, a rotor rotatable in and capable of an axial movement in said pumping chamber, means connecting the shaft and rotor whereby the shaft will rotate the rotor but not interfere with its axial movement, means actuated by 40 said rotor for pumping fluid, and a spring exerting pressure against the back of the rotor for forcing the rotor axially against one wall of the pumping chamber.

45 16. A rotary pump comprising a casing containing a pumping chamber with an intake to and discharge from said chamber, a

driving shaft, a rotor rotatable in and capable of an axial movement in said chamber, an anti-friction bearing supporting the rotor, means connecting the shaft and rotor whereby the shaft will rotate the rotor but not interfere with its axial movement, means actuated by said rotor for pumping fluid, a spiral spring engaging a portion of 55 said bearing and pressing the rotor axially toward one end of the pumping chamber, and means for conducting pressure accumulated by the pump to the back of the rotor for supplementing the tension of said spring. 60

17. A rotary pump comprising a casing containing a pumping chamber with an intake to and discharge from said chamber, and a pressure chamber communicating with the pumping chamber, a driving shaft, a 65 rotor rotatable in and capable of an axial movement in said chamber, means connecting the shaft and rotor whereby the shaft will rotate the rotor but not interfere with its axial movement, means actuated by said 70 rotor for pumping fluid, and means for conducting discharge pressure from the pump to the pressure chamber back of the rotor.

18. A rotary pump comprising a casing containing a pumping chamber with an intake to and discharge from said chamber and a pressure chamber communicating with the pumping chamber, a driving shaft, a rotor rotatable in and capable of an axial movement in said chamber, an anti-friction bearing supporting the rotor, means connecting the shaft and rotor whereby the shaft will rotate the rotor but not interfere with its axial movement, internally toothed and externally toothed intermeshing gears actuated by said rotor for pumping fluid, a spring in the pressure chamber and thrusting against said rotor bearing for initially forcing the rotor and gears axially toward one end of the pumping chamber, and means for 80 conducting accumulated discharge pressure to the pressure chamber back of the rotor for supplementing the tension of said spring. 85
